UNITED STATES PATENT OFFICE

138,816

DESIGN FOR A FERRULE FOR BINOCULARS

Charles J. Glasser, Chicago, Ill.

Application July 3, 1944, Serial No. 114,290

Term of patent 14 years

(Cl. D57—1)

To all whom it may concern:

Be it known that I, Charles J. Glasser, a citizen of the United States, residing at Chicago, in the county of Cook and State of Illinois, have invented a new, original, and ornamental Design for a Ferrule for Binoculars, of which the following is a specification, reference being had to the accompanying drawing forming a part thereof.

In the drawing,

Figure 1 is a perspective view of a ferrule for binoculars showing my new design; and

Fig. 2 is an enlarged sectional view substantially on the line 2—2 of Fig. 1.

I claim:

The ornamental design for a ferrule for binoculars, substantially as shown.

CHARLES J. GLASSER.
